(57) **CLAIM**

The ornamental design for a camera equipped network door station, as shown and described.

DESCRIPTION

FIG. 1 is a perspective view of a camera equipped network door station showing our new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof; and,

FIG. 7 is a left side elevational view thereof.

The broken lines represent environmental structure and/or unclaimed portions of the camera equipped network door station and do not form part of the claimed design.

1 Claim, 4 Drawing Sheets
